United States Patent [19]

Ottmann

[11] Patent Number: Des. 309,129

[45] Date of Patent: ** Jul. 10, 1990

[54] L-SHAPED ELECTRICAL CONNECTOR

[75] Inventor: David M. Ottmann, Mississauga, Canada

[73] Assignee: Connector Manufacturing Company, Cincinnati, Ohio

[**] Term: 14 Years

[21] Appl. No.: 857,608

[22] Filed: Apr. 24, 1986

[52] U.S. Cl. D13/149

[58] Field of Search D13/11, 12, 18-31;

[57] CLAIM

The ornamental design for an L-shaped electrical connector, as shown and described.

DESCRIPTION

FIG. 1 is a side elevational view of the L-shaped electrical connector showing my new design.

FIG. 2 is a front elevational view thereof.

FIG. 3 is a top plan view thereof.

FIG. 4 is a rear elevational view thereof.

FIG. 5 is a bottom plan view thereof.

[57]

CLAIM

The ornamental design for an L-shaped electrical connector, as shown and described.

DESCRIPTION

FIG. 1 is a front and top perspective view of a multiple compartment waste container showing my new design; FIG. 2 is a right side elevational view thereof, the left side elevational view being a mirror image; FIG. 3 is a front elevational view thereof; FIG. 4 is a top plan view thereof; FIG. 5 is a rear elevational view thereof; FIG. 6 is a bottom plan view thereof; and, FIG. 7 is a top and front perspective view thereof with the lid in open condition, and one of the compartment being elevated from the bottom for clarity of illustration.

REEXAMINATION CERTIFICATE
ISSUED UNDER 35 U.S.C. 307THE PATENT IS HEREBY AMENDED AS
INDICATED BELOW.

Matter enclosed in heavy brackets [ ] appeared in the
patent, but has been deleted and is no longer a part of the
patent; matter printed in italics indicates additions made
to the patent.

2
ONLY THOSE PARAGRAPHS OF THE
SPECIFICATION AFFECTED BY AMENDMENT
ARE PRINTED HEREIN.

5 FIG. 6 description added to specification.
FIG. 6 is a rear perspective view thereof.

AS A REESULT OF REEXAMINATION, IT HAS
BEEN DETERMINED THAT:

The single claim is cancelled.
